RAIL FROG

August Enstrom, Chicago, Ill.

Application August 17, 1936, Serial No. 96,333

3 Claims. (Cl. 246—468)

This invention relates to railway frogs and has for its object a construction wherein the point of the frog is at all times so positioned that it will not be broken or damaged by the operation of car wheels over and through the frog.

Among its other objects the present invention contemplates a frog, preferably a spring frog, over and through which traffic may move in both directions, if this be desired.

With the above and other objects in view, as will be apparent this invention consists in the construction, combination and arrangements of parts, all as hereinafter more fully described, claimed and illustrated in the accompanying drawings, wherein:

Fig. 1 is a plan view of a railway frog constructed in accordance with the present invention.

Fig. 2 is a vertical, transverse section taken along line 2—2 of Fig. 1 and, in dotted lines, illustrates the cooperation of a car wheel with the frog.

Fig. 3 is a fragmentary, longitudinal vertical section taken along line 3—3 of Fig. 2 to illustrate in side elevation the construction and form of the point of the frog: and

Fig. 4 is a horizontal section taken along line 4—4 of Fig. 2 looking upwardly in the direction of the arrows.

Heretofore it has been generally customary to normally position the point of a railway frog as close as possible to the head and/or web of the cooperating rail. This positioning of the point of the frog has resulted in great wear, tear and damage to the point of the frog as well as in the breakage thereof, necessitating the frequent repair and replacement of the frog or at least its point. These prior frogs, especially in spring frogs, have been usually designed for traffic in only one direction.

The present invention contemplates a railway frog in which the point of the frog is at all times positioned at a point removed from the head and/or web of the cooperating rail, so that the flange of a car wheel operating over or through the frog will not contact the point of the frog, irrespective of the direction of travel. Thus the life of the frog is extended, repairs and replacements reduced and potential derailments eliminated. Traffic in both directions is possible by the use of the present frog without damage or breakage to the frog or its parts or elements.

Reference being had to the drawings 10 designates the point of a rail frog. One side of the

frog point 10 aligns with and is fixed to a running or main line rail 11 while the other side of the point 10 aligns with and is fixed to the rail 12 of the side or crossing track. Extending beyond the point 10 of the frog and normally in alignment with the running rail 11 is a continuing running rail 13, the extremity 14 of which lies adjoining the frog point 10 and the side track or crossing rail 12. The extremity 14 of the rail 13 is known as the moving wing rail, as it may move outwardly away from the frog point 10. On the other side of the frog point 10 to the rail 13 is located a side track or crossing rail 16 which can be positioned to be a continuation of the side or crossing rail 12 fixed to the frog 15 point 10.

The extremity 16 of the rail 15 is formed to lie on the opposite side of the frog point 10 to the extremity 14 of the rail 13 and is generally designated the stationary wing rail since 20 it is immovable with respect to the fixed frog point 10. The foregoing described arrangement and construction of rails is standard and well known prior to the present invention and is included herein to illustrate the application and 25 use of the present invention in a standard frog construction. Heretofore the frog point has rested flush against the inner surface of the moving wing rail with the result that it is subjected to extreme wear and tear and is not infrequently 30 broken and must be replaced or repaired.

The present invention resides in the construction and form of the point 10 of the frog whereby said point at all times will be removed from the web and/or tread of the adjoining portion or face of the rail 13 or the moving wing rail 14 with which it normally cooperates. This is accomplished by bending or forming the web 17 of the end portion of the frog point 10 at the points 18 and 19 away from the web 20 of the rail 13 and its extension 14 which normally removes said end portion of the point 10 from any contact with the head and/or web of the rail 13 and the moving wing rail 14 and provides a space 21 between the moving wing rail and the end portion of the frog point 10 sufficient in width to permit the entrance and passage of the flange 22 of a car wheel 23.

If desired the outer extremity of the web 17 may be bevelled or tapered as illustrated at 50 24 in Fig. 4 thereby reducing the width of the metal body presented to the flange 22 of the car wheel 23 passing over the point 10 or between said point and the rail 13 and its extension 14. At its outer extremity the tread or head of the 55

frog point 10 is cut away as at 25, to add to the strength of the point by removing any relatively thin body on the head or tread of the point 10 that may be presented to the wheel 23 or its flange 22.

To accentuate the space 21 between the point 10 and the head and/or web of the rail 13 and its extension 14 and thereby insure the provision and maintenance of this space 21, the rail 13 and the moving wing rail 14 is bent or formed in a direction away from the frog point 10 at 26, 27, the bend 27 being at or nearly in transverse alignment with the end portion of the frog point 10. When the point 10 occupies its normal position in cooperation with the moving wing rail 14, that side of the point 10 aligned with the main or running rail 11 is also aligned with the rail 13 beyond the bend 26 therein.

In operation, a car wheel 23 travelling on rail 13 and passing over the frog point 10 to the rail 11, or vice versa, does so without interference from or damage to the point 10 for the point normally occupies a position for such operation with edges of its head and of the heads of the rails 11 and 13 in alignment for cooperation with the flange 22 of the wheel 23. On the other hand, a wheel 23 passing in either direction from the rail 12 to the rail 15 does so by having its flange enter the space 21 between the point 10 and the moving wing rail 14, also without contacting the extremity of the point 10.

From the foregoing, it is manifest that irrespective of the direction of travel or of the rails being operated upon, the extremity of the point 10 is always positioned out of the path of travel

of the flange 23 of the wheel and is thus fully protected from damage or breakage. It is also to be noted that by having the extremity of the point 10 spaced from the rail 13 and/or the moving wing rail, travel in either direction is possible on the rails 12 and 15 without damage to the frog point. 5

What is claimed is:

1. A rail frog comprising a moving wing rail, and a frog point having convergent sides, the 10 end portion of the side of the point adjoining said wing rail being positioned at an angle to the remainder of that side in a direction away from said wing rail to create a space between the end of the frog point and the wing rail. 15

2. A rail frog comprising a running rail, a moving wing rail coacting therewith, and a frog point having convergent sides, one of said sides being aligned throughout with one side of the running rail and the end portion of the opposite 20 side being disposed at an angle to the remainder of said opposite side, thereby creating a space between the end of the point and the cooperating wing rail.

3. A rail frog, comprising a fixed frog point 25 having convergent sides and a moving wing rail normally contacting one side of said frog point, for a substantial distance at the rear of its end portion, the side of said end portion of the frog point facing said wing rail lying in a substantially 30 vertical plane disposed at an angle to the plane of the remainder of said side and extending in a direction away from said moving wing rail.

AUGUST ENSTROM. 35
